2 SHEETS—SHEET 2.

UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

GUN.

1,257,501.

Specification of Letters Patent. Patented Feb. 26, 1918.

Application filed October 4, 1916. Serial No. 123,645.

To all whom it may concern:

Be it known that I, CHARLES F. LEFEVER, a citizen of the United States of America, residing at Plymouth, in the county of Wayne and State of Michigan, have invented 5 certain new and useful Improvements in Guns, of which the following is a specification, reference being had therein to the accompanying drawings.

10 It is one of the objects of the invention to obtain a construction of gun that may be knocked down and re-assembled without disturbance of any part of the operating mechanism. It is a further object to obtain various improved features of construction as 15 hereinafter set forth.

In the drawings:

Figure 1 is an elevation of the gun assembled;

20 Fig. 2 is a similar view with the stock removed;

Fig. 3 is a longitudinal section through a portion of the barrel and frame;

25 Fig. 4 is a similar view illustrating the operation of the lever mechanism;

Fig. 5 is a fragmentary longitudinal section;

Fig. 6 is a cross section on the line $\alpha-\alpha$ of Fig. 4.

30 The invention has special reference to a spring-actuated air gun, and more particularly to that type in which the spring is compressed by a longitudinally-movable handle for pump action. Heretofore guns 35 of this type have been made with removable stocks, but it is usual to mount some portion of the mechanism on each of the separable members. Thus, where the barrel is detachable from the frame and stock, care and a 40 certain amount of skill must be exercised in re-assembling the parts to render the mechanism operative. In the same manner where the stock is removed some portion of the mechanism, as for instance the trigger or 45 sear, is carried thereby, so that skill is also required in re-assembling. With the present invention all of the mechanism, including trigger and sear, is carried by the barrel section, so that the stock may be removed 50 and replaced without disturbance thereof.

In detail, A is the barrel and B a frame 55 permanently attached thereto and preferably formed integral therewith. C is the stock which is provided at its forward end with a frame member D telescopically en-

gagable with the frame member B and secured thereto by a single screw or fastening pin E. This fastening device is so arranged that it may be inserted and withdrawn without interference with the operating mechanism, all of the parts of which are mounted on the members A and B.

60 The operating mechanism comprises an air compression cylinder F, a piston G therein provided with a rearwardly-extending shank H, a spring I sleeved on this shank, a lever mechanism for withdrawing this shank and a sear and trigger for retaining and releasing the shank. The cylinder, piston and spring are preferably inserted as a 65 unit through the open rear end of the frame B and are anchored in position, first, by an abutment J in the barrel A, and second, by a detachable abutment K for the inner end of the spring. The abutment J is preferably 70 a tubular bushing, which is inserted into the barrel A and is permanently attached thereto, preferably by spot welding. The air compression cylinder F is provided with a piston abutment L secured therein, which 75 abutment bears against the bushing J and holds the cylinder and piston from forward movement. For anchoring the spring I the abutment K is preferably formed of a 80 stamping or pressed sheet-metal member, 85 which is insertable through an aperture M in the lower side of the barrel, having a tongue portion K' engaging a recess in the upper side of the barrel and also provided with rearwardly-extending flanges K² which 90 fit within the bore of the barrel. To engage the abutment, the spring is first placed under compression by a suitable instrument so as to move its rear end forward beyond the aperture M. The member K may then be 95 inserted, said member extending between the parallel sides of the shank H which is bifurcated, and when inserted the spring I is released so as to press upon the abutment, forcing the flanges K² into the bore of the 100 barrel in rear of the aperture M and thereby holding said abutment from displacement.

105 The mechanism for compressing the spring comprises the handle N slidably secured to the barrel, and the toggle lever having the members O and O' pivotally attached to each other, the one being pivoted to the handle N and the other fulcrumed on the pin P in the frame. These lever members O and O' are preferably formed of sheet- 110

metal bent into a U-shaped cross section, and the member O' is embraced by the parallel flanges B' of the frame. The operative connection between the toggle levers O and O' and the shank of the piston is formed by a lever Q pivoted at Q' near the lower edge of the frame, and having its free end fashioned to engage with the bearing R and the rear end of the piston shank H. The lever 5 Q is connected to the lever O' by a link S, and the angular relation of the parts is such that the lever O' and link S constitute a toggle normally bent or straightened as they are moved rearwardly. This will increase 10 the power of the movement in proportion to the increased tension of the spring, as the piston and its operating shank are moved rearward. T is a sear pivoted at T' to the frame and having a hooked end T² for engaging 15 with the bearing R. U is the trigger pivoted at U' and having a portion U² engaging the sear to operate the same. The trigger U is also provided with a forwardly-projecting portion U³ which is in proximity 20 to a safety catch V, the latter being in the form of a bell-crank lever, one arm V' of which bears against the lever Q when the latter is in normal position. The arrangement is such that when the lever Q is swung 25 rearward the safety catch V is permitted to move under the actuation of the spring W, which will engage the end V² of said catch beneath the projection U³ of the trigger locking said trigger from movement. Thus 30 the trigger and sear will be held in locked position during the entire movement of actuating the levers O and O' and compressing the spring, and it is only when the actuating levers are restored to normal position and 35 the lever Q swings forward that it will engage the catch V and withdraw the same from interference with the trigger.

In operation, the rearward movement of the handle N will break down the toggle levers O and O', which in turn will actuate the link S and the lever Q. It will be noted that in the swinging of the lever Q its arc of movement is the reverse of the arc traversed by the lever O' at the point of its 45 pivotal connection with the link S. This retains said link S at a favorable angle to the lever Q during the greater part of the movement, while the said link S and the lever O' are progressively straightened or 50 moved into alignment to produce increased power.

What I claim as my invention is:—

1. In a gun, a barrel and frame section, operating mechanism mounted in complete 60 operative relation upon said barrel and frame section, and a stock section telescopically engaging said barrel and frame section and secured thereto without interference with said mechanism, the telescoping portion 65 of said stock section surrounding the

telescoping portion of said barrel and frame section.

2. In a gun, a barrel section having a shoulder or abutment therein, an air compression cylinder, a piston, an operating shank and a spring, all of the said parts being insertible into the barrel from the rear end thereof into engagement with said abutment, and an abutment for the rear end of the spring laterally engageable with said 75 barrel.

3. In a gun, a barrel section having a shoulder or abutment therein, air compression means comprising a cylinder, a piston, a piston shank and a spring, all insertible 80 in said barrel through the rear end thereof, with the cylinder in engagement with said abutment or shoulder, and an abutment for the rear end of the spring laterally insertible through an aperture in said barrel and having a locking shoulder for retaining the same from disengagement when under the pressure of the spring.

4. In a gun, the combination with a barrel section having a shoulder or abutment 90 therein, of air compression means comprising a cylinder, a piston therein, a bifurcated piston shank and a spring sleeved on said shank, all of said parts being insertible in the barrel through the rear end thereof, and an abutment for the rear end of the spring laterally insertible through an aperture in 95 said barrel and between the furcations of said shank, said abutment having a shoulder for holding the same from disengagement 100 when under the pressure of the spring.

5. In a gun, a barrel section having parallel side plates depending therefrom, constituting a frame, a break-down lever extending parallel to said barrel and having its 105 rear link pivoted between the side plates of said frame, a plunger shank retractible rearwardly in said barrel, a lever for directly actuating said shank fulcrumed at its lower end between said side plates of the 110 frame, a link connecting said lever with the rear member of said break-down lever and constituting in connection therewith a toggle which is progressively straightened, a sear for engaging said piston shank, a 115 trigger for releasing said sear, all of said parts being mounted on said barrel and frame.

6. In a gun, the combination with a barrel section having depending parallel side 120 plates constituting the frame, a piston shank in said barrel, a lever for directly actuating said shank pivoted at its lower end between said side plates, a lever pivoted between said side plates at a higher point, and a link 125 connecting said levers at points describing arcs of movement substantially in reverse directions.

7. In a gun, the combination with a barrel, of depending parallel side plates constitut- 130

- ing a frame, a piston shank movable rearwardly in said barrel, a lever for directly actuating said shank pivoted at its lower end between said side plates, an operating lever 5 fulcrumed between said side plates at a point above the pivot for the first-mentioned lever, and a link connecting said levers, arranged substantially at right angles to said first-mentioned lever in its initial position 10 and pivotally connected to said second-mentioned lever at a point below its fulcrum.
8. In a gun, a barrel, a frame depending therefrom and apertured to form a trigger guard, a lever mechanism fulcrumed in said 15 frame, a trigger mounted in said frame, having its actuating portion in registration with said aperture, and a safety catch for said trigger in the form of a bell-crank lever adjacent to said guard, one arm of said lever 20 being in engagement with said lever mechanism when in normal position to unlock the trigger, and being released from said lever mechanism during its initial movement to lock said trigger.
- 25 9. In a gun, a unit comprising a barrel section, a frame section having parallel side plates depending from the barrel, air compression means comprising a piston, an operating shank and a spring, all arranged with- 30 in said barrel section, and mechanism mounted in said frame section, including a sear, a
- spring therefor, a trigger, and a compound lever pivoted at one end in said frame and slidably mounted upon said barrel section at the other end, and a stock section engageable 35 with and disengageable from said frame section without interference with said mechanism.
10. In a gun, a barrel and frame section, operating mechanism mounted in complete 40 operative relation on said barrel and frame section including a trigger, and a telescopic stock section engageable with and disengageable from said barrel and frame section without interference with said mechanism, 45 said telescopic stock section extending to a point in advance of said trigger.
11. In a gun, a barrel section and parallel side plates depending therefrom constituting a frame, a portion of said side plates 50 being cut away to form a trigger opening and guard, a compound lever mounted between the side plates of said frame, a trigger also mounted on and between said side plates and having its actuating portion ex- 55 tending into registration with said openings and a stock section engageable with and disengageable from said barrel section without interference with said lever and trigger mechanism. 60

In testimony whereof I affix my signature.
CHARLES F. LEFEVER.
